US00D933410S

(12) **United States Design Patent** (10) **Patent No.:** **US D933,410 S**
Jeon (45) **Date of Patent:** **** Oct. 19, 2021**

(54) **WATER PURIFIER**

- (71) Applicant: **Coway Co., Ltd.**, Gongju-si (KR)
(72) Inventor: **Jung Jae Jeon**, Seoul (KR)
(73) Assignee: **Coway Co., Ltd.**, Gongju-si (KR)
(**) Term: **15 Years**
(21) Appl. No.: **29/707,063**
(22) Filed: **Sep. 25, 2019**

Related U.S. Application Data

- (62) Division of application No. 29/629,794, filed on Dec. 15, 2017, now Pat. No. Des. 868,522.

(57) **CLAIM**

The ornamental design for a water purifier, as shown and described.

DESCRIPTION

FIG. 1 is a top, front, right side perspective view of the water purifier;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures show portions of the water purifier that form no part of the claimed design.

1 Claim, 7 Drawing Sheets
